UNITED STATES PATENT OFFICE.

OLIVE VIOLA CAMP, OF DENVER, COLORADO.

CATAMENIAL SACK.

Application filed December 9, 1922. Serial No. 605,855.

To all whom it may concern:

Be it known that I, OLIVE V. CAMP, a citizen of the United States, residing at Denver, in the county of Denver and State of Colorado, have invented new and useful Improvements in Catamenial Sacks, of which the following is a specification.

The object of my invention is to improve catamenial sacks by the provision of a simple, inexpensive, easily applied and efficient protective covering, designed to be worn over a period napkin with a view to preventing soiling of underwear, and one that is cool and sanitary and comfortable.

15 I contemplate making the protective covering in two sizes, medium and large, the large size for hospital use and for the use of very large women.

To the attainment of the foregoing, the 20 invention consists in the improvement as hereinafter described and definitely claimed.

In the accompanying drawings, forming part of this specification:—

Figure 1 is a plan view of my novel protective covering per se.

Figure 2 is a transverse section taken in the plane indicated by the line 2—2 of Figure 1.

Figure 3 is a transverse section showing 30 the covering combined with a folded napkin or gauze filling to form a catamenial sack.

Figure 4 is a detail view showing the manner in which an ordinary safety pin is employed to connect the covering portions at 35 each end of the sack.

Similar numerals designate corresponding parts in all of the views of the drawing.

The filling of the catamenial sack, which 40 may be a folded period napkin or folded gauze or other absorbent material, is designated by 1 in Figure 3, while my novel protective covering as a whole is designated by 2.

45 Among other elements the protective covering comprises a sheet 3 of thin and soft and flexible vulcanized rubber or equivalent material, the side edges being turned over as at 4, and vulcanized. The sheet 3 is bifurcated at its ends as designated by 6, and its 50 portions 7 at opposite sides of the bifurcations are preferably, though not necessarily, of double thickness for the sake of increased strength. Each of the said portions 7 is 55 provided with an eyelet 8. In the sheet 3

is a longitudinally centrally elongated opening 9, surrounded at the outer side of the covering, by a head 10 which is rounded or of circular cross section and is preferably, though not necessarily, integral with the 60 sheet 3.

Two ordinary safety pins are designed to be used in conjunction with the filling 1 and protective covering 2, one of the said safety pins being shown in Figure 4, and designated by 11.

As will be readily understood from Figures 1 and 2, my novel protective covering is very compact, and may be carried in a package of small compass; also, the outwardly curved side portions of the covering serve, when the covering is on a folded napkin or other absorbent filling, to prevent blood from passing through the covering. The bead 10 of the covering serves effectively in preventing discomfort to the person wearing the catamenial sack of which the covering forms a part.

In the practical use of my novel protective covering it is folded about a soft filling 1 80 in the manner shown in Figure 3, with the opening 9 above the filling 1 so as to enable the menstrual discharge to reach and be absorbed by the said filling. The end portions 7 of the covering are connected by 85 safety pins as 11 which are passed through the eyelets 8, and also through a portion of the filling 1, the latter to hold the filling against endwise movement relative to the covering. In this connection, it will be understood that when the end portions 7 are 90 connected by two safety pins, one pin to each pair of end portions 7, the longitudinal or side edges of the covering will be tightly held in lapped relation at the underside or 95 outer side of the filling, and hence will prevent the passage of blood.

I have entered into a detailed description of the construction and relative arrangement of the parts embraced in the present 100 and preferred embodiment of the invention, in order to impart a full, clear and exact understanding of the said embodiment. I do not desire, however, to be understood as confining myself to the specific construction 105 and relative arrangement of parts inasmuch as in the future practice of the invention, various changes and modifications may be made such as fall within the scope of my invention as defined in my appended claims. 110

Having described my invention, what I claim and desire to secure by Letters Patent, is:

1. A protective covering for use as part of a catamenial sack, formed of soft and flexible water-proof material, and having a longitudinal central elongated opening and outwardly curved longitudinal or side edges, and also having bifurcations in its ends and 10 eyelets upon opposite sides of said bifurcations.

2. A protective covering for use as part of a catamenial sack, formed of soft and flexible water-proof material and having a longitudinal central elongated opening and outwardly curved longitudinal or side edges and also having bifurcations in its ends and 15 eyelets upon opposite sides of said bifurcations; the said longitudinal central elongation-

ated opening being surrounded by a bead of 20 rounded cross section disposed at the outer side of the covering.

3. A protective covering for use as part of a catamenial sack, formed of soft and flexible water-proof material and having a longitudinal central elongated opening and outwardly curved longitudinal or side edges, and also having bifurcations in its ends and 25 eyelets upon opposite sides of said bifurcations; the said longitudinal central elongated 30 opening being surrounded by a bead of rounded cross section disposed at the outer side of the covering, and the longitudinal or side edges being reinforced by turning these edges over and vulcanizing the same 35 to the body.

In testimony whereof I affix my signature.

OLIVE VIOLA CAMP.
